United States Patent Office

Des. 215,554
Patented Oct. 7, 1969

215,554

DRINKING GLASS

Edward W. Koch, Whippany, and David C. Dorsi,
Stirling, N.J., assignors to Sterling Glass Laboratories,
Inc., Stirling, N.J., a corporation of New Jersey

Filed Apr. 23, 1968, Ser. No. 11,573

Term of patent 14 years

Int. Cl. D7—01

U.S. Cl. D36—8

FIG. 2.

FIG. 3.

FIG. 1 is a top plan view of a drinking glass showing our new design;

FIG. 2 is an elevational view thereof; and

FIG. 3 is a sectional view on line 3—3 of FIG. 1.

We claim:

The ornamental design for drinking glass, as shown.
